AUTOMATIC VOLUME CONTROL SYSTEM

Harold P. Spearin, Chicago, Ill., assignor to
Alfred Crossley, Chicago, Ill.

Application December 14, 1935, Serial No. 54,464

5 Claims. (Cl. 250—20)

This invention relates to an automatic volume control system for a radio signal receiver, and more especially to such a system wherein large AVC voltages are developed without the use of 5 separate amplification.

One object of this invention is to provide a system wherein automatic volume control voltage is obtained, without the use of a diode rectifier, in a tube circuit which provides both the automatic volume control voltage and the required 10 tube characteristics for demodulation of a received radio frequency signal; another object of this invention is to provide an economical system which will produce relatively large voltages for 15 automatic volume control purposes, without recourse to the use of an additional tube and circuit particularly for automatic volume control purposes; yet another object of this invention is to provide a source of automatic volume control 20 voltage in a detector tube and associated circuit, the magnitude of which voltage is substantially equivalent to that obtained by means of an additional amplifying tube feeding into a diode or rectifier circuit; a still further object of this 25 invention is to provide additional means in a tube prior to the detector, whereby an increased voltage for automatic volume control purposes can be obtained from the detector tube and associated circuit; other features and advantages 30 of the invention will be apparent from the following specification and the drawings, in which—

Fig. 1 is a diagrammatic view of a part of a radio signal receiving system embodying the invention; Fig. 2 is a diagrammatic view of a diode used to stabilize the system; Fig. 3 is a diagrammatic view of a modification employing a battery to obtain greater AVC voltages; Fig. 4 is a diagrammatic view of a system wherein a rectifying tube provides a source of substantially constant 40 voltage to replace the battery of Fig. 3; and Fig. 5 is a diagrammatic view of a portion of a radio signal receiver wherein the screen grid voltage of the detector tube is varied in accordance with the strength of the incoming signal to increase 45 the automatic volume control voltage developed in that tube.

Modern radio signal receivers practically all 50 incorporate an automatic volume control system wherein a DC biasing potential is developed proportional to the strength of the incoming signal 55 and applied to the grid systems of one or more tubes having varying amplification factors. In order to have a comparatively flat output through conditions varying from a weak signal of perhaps 10 microvolts to the strong signal of a nearby

powerful broadcasting station, it is necessary to develop comparatively high voltages for automatic volume control purposes. This has generally been done by diverting a portion of the signal passing through the radio receiver, amplifying it in a tube used for this purpose alone, and then rectifying it by a diode or other similar means. Such a system develops the necessary voltage swing for good automatic volume control purposes, but is expensive in that it requires 10 either two additional tubes or a single dual purpose tube with associated circuits. The automatic volume control system disclosed herein obtains a voltage swing equivalent to the amplified 15 automatic volume control system, yet uses 10 neither a separate tube nor a dual purpose tube, at least in its simplest form. The present system employs only, in addition to the apparatus necessary in the receiver, a voltage divider or potentiometer which makes use of changes in the plate 20 current in the detector tube to develop the various DC voltages desirable for automatic volume control purposes.

In the particular embodiment of this invention illustrated in Fig. 1, a portion of a radio signal receiving system is illustrated having two radio frequency amplifying tubes 10 and 11 and a detector tube 12. These tubes are illustrated as pentodes, since this type of tube is more sensitive than a triode, although for the purposes of this 25 invention a three-element tube will achieve the desired results. The three tubes shown have associated therewith tuning or tank circuits comprising inductances 13, 14 and 15 and variable condensers 16, 17 and 18. These condensers are 30 preferably ganged for simplified tuning. The radio frequency impulses picked up by the aerial 19 are developed across the primary inductance 20, which in turn develops radio frequency voltages in the tank circuit comprising the inductance 13 and the condenser 16. The voltages of the frequency to which this circuit is tuned are 35 then developed on the grid 21 of the tube 10, and the amplified signal passes from the plate 22 through the primary 23, and is transferred to 40 the inductance 14 and developed on the grid 24 of the tube 11. The amplified current from this tube passes from the plate 25 through the primary inductance 26, and is transferred to the inductance 15 and developed between the grid 27 and 45 the cathode 28 of the detector tube 12. The biasing resistor 29 in the cathode circuit of this tube, in series with the resistor 32 to the B voltage supply, keeps the grid at a negative potential 50 and causes the tube to demodulate the radio signal 55

nal carrier wave, so that an audio frequency output is had from the plate 30 of this tube. The audio frequency voltage is here shown as developed across the plate load resistor 31 and passed through the filter resistor 32 and condenser 33, whence the leads 34 and 35 apply it to the audio frequency amplifying system of the receiver, not here shown since it forms no part of the present invention.

10 The plate supply or B-voltage comprising battery voltage or the rectified output of a power-pack, is developed across a voltage divider here shown as comprising the resistors 36 and 37 and the speaker field 38. The point 39 between the 15 resistor 37 and the speaker field 38 is grounded, so that the voltage supply is partly above and partly below ground potential, since the cathodes 40 and 41 of the radio frequency amplifying tubes 10 and 11 are grounded. The B-voltage 20 supply is thus partly positive and partly negative with respect to the cathode potential of these last-mentioned two tubes. The substantially direct current B-voltage supplied by this 25 voltage divider system is developed across a potentiometer comprising the plate load resistor 31 and the resistors 42, 43, and 44. The point 45 on the potentiometer between the resistors 43 and 44 is connected through the filter resistors 46 and 47, respectively, to the grids 24 and 21 of 30 the tubes 11 and 10. The voltage of the point 45 on the potentiometer is thus applied at all 35 times to the grids of the radio frequency amplifying tubes and serves to control the amplification factor of these tubes in accordance with the strength of the incoming signal, since variations in signal strength cause variations in the voltage of the point 45 with respect to ground, and consequently with respect to the cathodes 40 and 41 of the tubes 10 and 11. It will be noted 40 that the B-voltage has two parallel paths, one through the potentiometer and the other through the tube 12. Both of these paths, however, have the plate load resistor 31 in common. The resistors 42, 43, and 44 are chosen of such value 45 that under normal conditions, that is, with little or no signal being received, the point 48 is at substantially ground potential, although not connected to ground. The resistor 43 is chosen of such size that with a normal current passing 50 through the potentiometer the point 45 is slightly negative with respect to the point 48, and therefore with respect to ground. There is thus normally a slight negative bias voltage applied 55 through the filter resistors 46 and 47 to the grids 24 and 21. The current through the load resistor 31 is a resultant of the current through the resistors 42, 43, and 44, and the space current in the tube 12 flowing from the cathode 28 to the plate 30. Since the space current through the 60 tube varies in accordance with the signal voltage impressed on the grid 27, the current through the plate load resistor 31, and therefore necessarily the voltage developed across that resistor, also varies. When the space current in the tube increases, due to an increased signal, the increased voltage developed across the plate load resistor 31 results in a lesser voltage drop across the three resistors 42, 43, and 44. Since the proportions are fixed by the resistor values, the voltage drop 65 across the resistor 44 will become smaller, or in other words the point 45 will become more negative with respect to ground and therefore with respect to the cathodes 40 and 41. The voltage applied to the grids 21 and 24 of the tubes 10 and 11 is therefore more negative than before 70

with respect to the cathode, and the amplification factor of the tubes is decreased thus reducing the signal strength applied to the grid 21 of the detector tube 12. In this manner variations in signal strength cause the biasing voltage applied to the grids of the radio frequency amplifying tubes to vary and thus automatic volume control is achieved.

5 In order to minimize the effects of undesired radio frequency voltages in the system, by-pass or filter condensers 49, 50, 51, 52, 53, 54, and 55 are inserted in appropriate parts of the circuit. The tubes 10, 11, and 12, in addition to control grids 21, 24, and 27, are provided with screen grids 56, 57, and 58, and with suppressor grids 59, 60, and 61, which last-mentioned grids are 10 here shown connected to the cathodes of the respective tubes. The voltage for the screen grid 58 of the tube 12 is supplied by the lead 62 from the point 63 in the B-voltage divider system. It 15 is understood that the screen grids 56 and 57 are similarly supplied with proper voltages from any convenient source, not here shown. Each of the tubes 10, 11, and 12 is also, of course, supplied with a heater and associated circuits not here 20 shown, in order to heat the cathodes 40, 41, and 25 28 to the emitting temperature.

30 In the particular receiver disclosed in this embodiment of the invention, a B-voltage of 370 was used, with 100 volts drop across the speaker field 38. A screen grid voltage of 43 volts was used and the cathode bias resistor 29 developed 2.8 volts bias under normal or no-signal conditions. The plate resistor 31 had a value of $\frac{1}{2}$ megohm and the resistors 42, 43, and 44, comprising the remainder of the potentiometer system, had values of 5 megohms, $\frac{1}{4}$ megohm and 2 megohms, respectively. Under these conditions, a variation from zero to $1\frac{1}{4}$ volts on the grid 27 of the particular detector tube 12 used resulted in a voltage change or swing of 85 volts 40 across the plate load resistor 31. The change in voltages across the various parts of the potentiometer system resulted in a $1\frac{1}{2}$ volt swing at point 45, or in other words, when there is a $1\frac{1}{4}$ volt signal applied to the grid 21, the resulting 45 change in the space current in the tube 12 causes the grids 21 and 24 in the radio frequency amplifying tubes 10 and 11 to be biased about $1\frac{1}{2}$ volts more negative than before, thus cutting 50 down the signal strength applied to the tube 12 and giving the desired automatic volume control. Where it is desired to secure a larger biasing voltage swing for the same detector grid voltage change, either a larger B-voltage may be used or 55 a greater proportion thereof developed across the speaker field 38, that is, below ground potential. Either of these methods has its disadvantages, however, since a substantial increase in total B-voltage requires a considerable increase in 60 power pack expense, and a different division of the B-voltage results in less positive voltage being available for the plate of each of the tubes, with a resultant loss in amplification. Other methods for increasing the biasing voltage swing 65 without the necessity for resorting to either of these two methods will be discussed hereafter.

70 In the particular embodiment of this invention illustrated in Fig. 2, the detector tube 12, in addition to the five elements shown in Fig. 1, is provided with a diode plate or rectifying element 64. This is connected by the lead 65 to the point 45 in the potentiometer system, which point is normally at substantially ground or cathode potential. In a laboratory or custom built receiver the 75

resistors 42, 43 and 44 of the potentiometer system can be carefully proportioned so that, in connection with a particular tube and plate load resistor 31, the point 48 is at substantially ground 5 or cathode potential. In factory methods of production, however, it is not always possible to perfectly match these resistors with the individual tubes, and to hold them within sufficiently close limits to keep the point 48 at the desired voltage. 10 The introduction of the diode plate 64 serves to stabilize the voltage of this point 48 and to hold it at or very close to the cathode potential under no-signal conditions. Should the point 48 tend 15 to be more positive than is desirable, a flow of electrons from the cathode 28 to the diode element 64 would tend to hold this point 48 at approximately cathode potential. The fact that a reverse flow of electrons cannot occur enables the point 48 to swing considerably negative when a 20 strong signal is impressed on the tube, and thus the automatic volume control effectiveness of the system is not impaired.

In the particular embodiment of this invention illustrated in Fig. 3, the potentiometer resistor 42 is replaced by a battery 66 and smaller resistor 83. The voltage of this battery is chosen to substantially equal the voltage drop across the resistor 42 under normal or no signal conditions. When this battery 66 is used it prevents a part of the voltage swing in the plate load resistor 31 from being absorbed in the resistor 42, and instead causes practically the entire voltage swing in the resistor 31 to be developed across the resistors 43 and 44. It is clear that this method causes a much larger proportion of the plate voltage swing to be developed across the resistor 44 and applied to the grids of the radio frequency amplifying tubes. Under the same conditions as those heretofore discussed in connection with Fig. 1, the circuit of Fig. 3 causes automatic volume control voltages well in excess of 20 volts to be developed. The overall amplification of the receiver of the volume curve can thus be held more nearly flat.

45 In the particular embodiment of this invention illustrated in Fig. 4, another system is used to develop a larger proportion of the voltage swing in the plate load resistor 31 across the resistor 44. In this case, the resistor 42 has a separate diode tube connected in parallel therewith, and the voltage across this resistor 42 is thus held at a substantially constant value. A diode tube 67 is here shown having a cathode 68 and a plate element 69. The cathode is connected to the top of the resistor 42 through the filter or split load resistance 70, part of this resistance and the condenser 84 forming a filter system for the output of this rectifier. The plate is connected through the secondary 71 of a transformer and the lead 72 to the bottom of the resistor 42. The primary 73 of this transformer may either be separately fed from the alternating current source or the entire transformer may be a part of the power-pack of the receiver. This system gives increased proportions of voltage swing across the resistor 44, with increased automatic volume control action, without the necessity of a dry cell battery in the receiver.

70 In the particular embodiment of this invention illustrated in Fig. 5, very effective automatic volume control is achieved, since the voltage on the screen grid 58 of the detector tube 12 is varied to increase the swing of the automatic volume control voltage as a result of change in
75

signal strength. In the circuit diagrammatically illustrated in this figure, the screen grid 58 is not supplied with voltage from the principal voltage divider comprising the resistor 14 and the speaker field 38, but is instead connected to the point 75 of the auxiliary voltage divider comprising the resistors 76, 77, and 78. These later named resistors are connected between B plus and ground and associated with the tube 11. The screen grid 57 of the tube 11 is connected to the point 79 on this voltage divider, and the current through resistors 76 and 77 and the screen grid current of the tube 11 both flow through the resistor 78. A change in the screen grid current in the tube 11 thus causes a change in the voltage of the point 75. Since this is the voltage applied to the screen grid 58 of the tube 12, there is thus a change in the space current flowing through the detector tube 12, and a consequent change in the voltage drop across the plate load resistor 31. The operation of this last-described system is substantially as follows: Under no signal conditions or light signal, the control grid 24 in the tube 11 is only slightly negative, and therefore a fairly large screen grid current is flowing. This screen grid current results in a relatively large voltage drop across the resistor 78, and the point 75 would normally be only 40 or 45 volts positive, the screen grid 58 in the detector 12 being at a like potential. A strong signal, however, causes an increase in the cathode to plate current in the detector tube 12, an increase in the voltage drop across the plate load resistor 31, and the point 45 in the potentiometer system becomes more negative with respect to ground. Since the voltage at the point 45 is applied to the control grid 24 in the tube 11 through the filter resistor 46, the grid 24 becomes more negative and cuts down the screen grid current flowing in the tube 11. This results in a smaller voltage drop across the resistor 78 with a consequent shift or swing of voltages across the three resistors 76, 77, and 78, so that the point 75 becomes more positive with respect to ground. The voltage on the screen grid 58 in the tube 12 is thus increased, causing a heavier space current to flow from the anode to the plate of the tube 12, and thus the swing of voltage of the point 45 is increased to result in stronger automatic volume control.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art. 60

What I claim as new and desire to secure by Letters Patent, is:

1. A radio signal receiving system, including: a radio frequency amplifying tube and a detector tube, each having a cathode, grid and plate; a source of substantially direct current voltage; means connecting the plate of said detector tube to the positive end of such source, said means including a plate load resistor; gain control means for supplying a variable bias to the amplifying tube connecting said plate of said detector to the negative end of said source, said means including a portion having a substantially constant voltage drop thereacross during application of the variable bias to said amplifying tube 75

during control action; and a connection between the grid of said amplifying tube and a point on said last-named means negative with respect to the cathode of said amplifying tube for rendering the gain control means effective.

5. Apparatus of the character claimed in claim 1, wherein said detector tube also contains a rectifying element and said element is connected to a point on said last-named means at substantially the potential of the cathode of said detector tube.

10. Apparatus of the character claimed in claim 1, wherein said portion comprises a resistor having the opposite ends thereof maintained at a substantially constant voltage differential by means of a rectifier tube and a source of alternating current voltage.

15. Apparatus of the character claimed in claim 1, wherein said portion comprises a resistor having the opposite ends thereof maintained at a substantially constant voltage differential by means of a rectifier tube and a source of alternating current voltage.

20. A radio signal receiving system, including: a radio frequency amplifying tube and a detector tube, each having a cathode, grid and plate; a source of substantially direct current voltage, one terminal thereof being negative with respect to the cathode of said amplifying tube; means connecting the plate of said detector tube to the positive end of said source, said means including a plate load resistor; gain control means for supplying a variable bias to the amplifying tube connecting said plate of said detector to the negative end of said source, said

means including a battery; and a connection between the grid of said amplifying tube and a point on said last-named means negative with respect to the cathode of said amplifying tube for rendering the gain control means effective.

5. A radio signal receiving system, including: a radio frequency amplifying tube and a detector tube, each having a cathode, grid and plate; a source of substantially direct current voltage, one terminal thereof being negative with respect to the cathode of said amplifying tube; means connecting the plate of said detector tube to the positive end of said source, said means including a plate load resistor; gain control means for supplying a variable bias to the amplifying tube connecting said plate of said detector to the negative end of said source, said means including a portion having a substantially constant voltage drop thereacross during application of the variable bias to said amplifying tube; and a connection between the grid of said amplifying tube and a point on said last-named means negative with respect to the cathode of said amplifying tube for rendering the gain control means effective, said constant voltage portion lying between said connection and the plate of said detector.

HAROLD P. SPEARIN.
